UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SHUTTLE FOR WEFT-REPLENISHING LOOMS.

1,204,084.

Specification of Letters Patent.

Patented Nov. 7, 1916.

Application filed October 12, 1915. Serial No. 55,382.

To all whom it may concern:

Be it known that I, EDWARD S. STIMPSON, a resident of Hopedale, in the county of Worcester and State of Massachusetts, have 5 invented certain new and useful Improvements in Shuttles for Weft-Replenishing Looms, of which the following is a specification.

The present invention consists in improvements upon the shuttle spring construction illustrated in United States Letters Patent of myself No. 1,074,908, October 7, 1913. In the construction of that patent the weft carrier holding spring, the weft carrier directing guide, and the spreader which maintains the jaws of the spring spaced correctly apart have to be independently handled and assembled in the shuttle. The shuttle spring has to be first put in place and held by the 20 fastening bolt; the spreader has to be inserted; the guide has to be then put in place and secured by an independent screw.

The object of the present invention is to preliminarily unite the spring, guide and spreader together so that it can be handled as a unit and be placed as such in the shuttle. The combined spring, guide and spreader is then fastened in place solely by the usual bolt for the spring.

30 The improvements are illustrated in the accompanying drawing's, wherein—

Figure 1, is a plan view of the weft-carrier holding end of the shuttle. Fig. 2, is a transverse section in the plane indicated by the line 2—2 in Fig. 3. Fig. 3, is a vertical section in the plane indicated by the line 3—3 in Fig. 2. Fig. 4, is a cross-section in the plane indicated by the line 4—4 in Fig. 3. Fig. 5, is a perspective view of the inclined guide of the weft carrier holding spring. Fig. 6, is a perspective view of the spreader.

In the drawings A, is the weft carrier holding spring which is bent into shape 45 from a single piece of metal substantially like that shown in the aforesaid patent.

B, is the weft carrier directing guide.

C, is the spreader.

D, is the bolt which fastens the spring, 50 guide and spreader to the shuttle E.

The spreader C, is a plate of the proper thickness to fit between the folded legs of the spring as illustrated in Fig. 2, and it is of the same height as the shank of the 55 spring, as shown in Fig. 3. As shown in

Fig. 6, it has a hole a, which registers with the holes in the shank legs of the spring, and it is through these holes that the bolt D, passes for securing the spring and spreader to the shuttle. The inner end of 60 the spreader is inclined at b, to fit the inner face of the incline c, of the guide when the parts are positioned as in Fig. 3. Hence, the spreader is maintained in proper position with respect to the spring with its hole 65 a, registering with the holes in the spring shank when the spring, spreader and guide are assembled prior to insertion in the shuttle.

The guide B, has the usual bottom plate 70 d, extending beneath the spring and fitting at its edges in slots in the shuttle body as indicated in Fig. 4. There is also a top plate e, this plate and the bottom plate being united together by the weft carrier 75 directing incline c. The top plate e, is constructed so as to lock the spring, spreader and guide together prior to insertion in the shuttle. When the spring, spreader and guide are assembled the top plate e, of the 80 guide is flat. The spreader is first placed in position between the legs of the spring and the guide is then put in place with its bottom plate d, below the spring and spreader and the top plate e, above the 85 spring and the spreader. The guide is pushed inwardly as far as it will go thus insuring the registration between the hole a, of the spreader and the corresponding 90 holes in the shank legs of the spring. The end and edges of the top plate e, are then bent downwardly as illustrated in the drawings. The sides f, are bent downwardly over the upper edges of the shank legs of the spring as illustrated in Fig. 4; and the 95 end g, of the top plate e, is bent downwardly back of the curved inner end of the spring A, as shown in Fig. 3. This effectually fastens the spring, spreader and guide together so that their proper relative positions are insured and the combined parts 100 can then be handled as a unit and can be placed in a shuttle as a single unit.

The united spring, guide and spreader are fastened to the shuttle by the usual 105 single bolt D, which is secured in place in the customary manner.

The bent down sides f, are bent outwardly at their lower edges to constitute flanges h, which fit within grooves i, of the shuttle. 110

this contributing and completing the arrangement to insure positively no movement of the combined parts. The bent down sides *f*, compensating for the greater height 5 of the spring shank as compared with the jaws, thus bringing the flanges *h*, down where they can fit into the grooves *i*, without danger of fracturing the wood of the shuttle:

10 The guide B, with its united bottom and top plates *d* and *e*, constitutes a bent metal retainer folded around the spring and spreader so as to lock them securely together with their bolt receiving holes in register.

15 I claim:

1. A shuttle for weft replenishing looms having, in combination, a bent weft carrier holding spring; a spreader fitting between the legs of said spring; and a weft carrier

20 directing guide, said guide having upper and lower plates united by the directing incline, said top and bottom plates extending respectively above and below the spring and spreader, the upper plate being bent at its 25 sides downwardly along the sides of the spring shank and thence extending laterally to form flanges adapted to fit within grooves in the shuttle, and the end of the top plate being bent downwardly back of the curved

30 inner end of the spring, whereby said spring, spreader and guide are united together prior to insertion in the shuttle, and said spreader having a bolt receiving hole adapted to register with the bolt receiving holes in the 35 shank of the spring and said spreader further having an inclined end adapted to fit the inner face of the directing incline of the guide.

2. A shuttle for weft replenishing looms 40 having, in combination, a bent weft carrier holding spring; a spreader fitting between the legs of said spring; and a weft carrier

directing guide, said guide having upper and lower plates united by the directing incline, said top and bottom plates extending 45 respectively above and below the spring and spreader, the upper plate being bent at its sides downwardly along the sides of the spring shank and thence outwardly to constitute flanges fitting grooves in the shuttle, 50 and the end of the top plate being bent downwardly back of the inner end of the spring, whereby said spring, spreader and guide are united together prior to insertion in the shuttle, and said spreader having a 55 bolt receiving hole adapted to register with the bolt receiving holes in the shank of the spring and said spreader fitting within the spring and guide so as to be maintained in position with its bolt receiving hole regis- 60 tering with the bolt holes of the spring.

3. A shuttle for weft replenishing looms having, in combination, a bent weft carrier holding spring; a spreader fitting between the legs of said spring; and a bent metal re- 65 tainer folded around said spring and spreader so as to lock the same together, the top plate of said retainer being bent downwardly outside of the shank of the spring, and outwardly to constitute flanges to fit 70 grooves in the shuttle.

4. A shuttle for weft replenishing looms having, in combination, weft carrier holding spring jaws; and a bent metal retainer having top and bottom plates above and below 75 the shanks of said jaws, one of said plates being bent so as to embrace the sides of the shanks of the jaws and thence outwardly to constitute side flanges to fit grooves in the shuttle, and the edges of the other plate like- 80 wise fitting grooves in the shuttle.

In witness whereof, I have hereunto signed my name.

EDWARD S. STIMPSON.
